UNITED STATES PATENT OFFICE.

HENRY W. HIRSCHFELD, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A CUP, BOWL, OR SIMILAR ARTICLE.

43,844.

Specification for Design.

Patented Apr. 15, 1913.

Application filed May 27, 1912. Serial No. 700,121. Term of patent 14 years.

To all whom it may concern:

Be it known that I, HENRY W. HIRSCHFELD, a citizen of the United States, residing at Meriden, in the county of New Haven and State of Connecticut, have invented a new, original, and ornamental Design for a Cup, Bowl, or Similar Article; and I do hereby declare the accompanying drawing to be a full, clear, and exact illustration of the same, and which said drawing constitutes part of this application, and represents a perspective view of a cup, bowl, or similar article embodying my design.

I claim:

The ornamental design for a cup, bowl or similar article, as shown.

HENRY W. HIRSCHFELD.
